UNITED STATES PATENT OFFICE

WILLIS H. CASTNER, OF CORNWALL, PENNSYLVANIA, ASSIGNOR TO BETHLEHEM STEEL COMPANY, OF BETHLEHEM, PENNSYLVANIA

KNOCK-OUT AND KICKER RIGGING ON BOLT-HEADING MACHINES

Application filed October 10, 1928. Serial No. 311,457.

My invention relates to a machine for heading bolts, rods, rivets and the like articles and more especially to the mechanism for forming the head and to the means for ejecting the headed article from the machine after the heading operation.

A further object relates to the manner of mounting the matrix, die and die-holder in a carrier which can be readily attached or detached from the machine as a unit, and substitute another unit therefor in case of breakage, or when it is desired to form heads of different sizes, thereby greatly decreasing the loss of time in changing the matrix and die and thereby increasing the rate of production of the machine.

Another object is to provide a means for positively ejecting the finished article from the matrix at the end of the heading operation.

Still another object of my invention is to provide means for positively detaching the finished article from the die after it has been ejected from the matrix by the die.

Other objects will appear hereinafter.

Referring now to the accompanying two sheets of drawings which form part of this specification and on which like characters of reference indicate like parts,

Figure 1 is a central vertical section of a portion of a forging or upsetting machine, illustrating the application of my invention, taken on the line 1—1 of Figure 3, the parts being in the position they will assume at the beginning of the forward stroke of the cross-head;

Figure 2 is a view similar to Figure 1, but showing the cross-head at the end of the working stroke;

Figure 3 is a top plan view of that part of the machine illustrated in Figure 1;

Figure 4 is a transverse section taken on the line 4—4 of Figure 1; and,

Figure 5 is a detail front elevation of the adjusting wedge.

Referring now to the various characters of reference on the drawings, the numeral 1 indicates the bed-plate and frame of the machine, having slide ways formed thereon as at 2 for receiving the reciprocating cross-

head 3 operated by means of a crank arm 4 mounted on the main drive shaft 5 through the pitman rod 6 and connecting pin 7.

The forward face of the cross-head is formed with a central vertical groove as at 8 to receive a wedge 9 adapted to be vertically adjusted by means of a set bolt 10 which is threaded through a split lug 11, projecting from the rear side of the wedge near the top thereof. The split lug 11 has a clamping bolt 12 extending transversely therethrough by means of which the sides of the threaded opening for the set bolt are adapted to bind against the set-bolt to lock it in its adjusted position. The lower portion of the wedge 9 is of channel section as at 13 in which is mounted a kicker-lever 14 pivoted at its upper end to the wedge as at 15, while the lower end of the kicker-lever extends below the bottom end of the wedge and is adapted to contact with a stop 16 which is secured to the bed-plate 1. The front face wall of the wedge has perforations formed therein as at 17 and 18 and a compression spring 19 is seated in a socket 20 in the kicker-lever 14 and engages the rear side of the front wall of the wedge to normally project the kicker-lever away from the same.

A bolster-plate 21 is attached to the lower portion of the face of the cross-head by means of bolts 22, the heads of which engage T-slots 23 formed in the face of the cross-head on either side of the wedge 9 by means of which the bolster-plate may be adjusted laterally if desired and is adapted to engage the face of the wedge and hold it in position. The bolster-plate is formed with a central opening 24 the side of which is formed with an annular extending boss 25 formed integral with the bolster-plate for holding the carrier 26, in which is mounted the matrix 27, of the size and shape of the head to be formed, die 28 and die-holder 29. Matrix 27 is secured to the carrier by means of a set-bolt 30, while the die which is adapted to reciprocate within the matrix is formed with a reduced end 31 for engaging a socket 32 in the forward end of the die-holder 29 and secured thereto by means of a pin 33. The die-holder is adapted to reciprocate in the carrier and

is formed at an intermediate point with an annular shoulder 34. A spring 35 is interposed between the front side of the shoulder 34 and an abutment 36 formed on the carrier 5 and is adapted to normally retract the die-holder and die attached thereto, while the rear side of the shoulder engages the face of the wedge to limit its backward movement. The rear end of the die-holder is formed with a reduced end 37 which extends through the slot 18 of the wedge and contacts with the kicker-lever 14.

In order to hold the carrier 26 in the central opening 24 of the bolster-plate 21, the bolster-plate 21 and boss 25 are split as at 38, having ears formed at either side thereof through which a clamping-bolt 39 extends by means of which the sides of the opening 24 are adapted to clamp the sides of the carrier 26 and the carrier is further secured by means of a set-bolt 40.

By this construction when it is desired to form a different shaped, or sized head on the article to be headed it is only necessary to release the clamping pressure on the bolt 39 and set-bolt 40, and the carrier can then be withdrawn from the central opening 24 in the bolster-plate 21 and another carrier inserted in place thereof having the desired 30 matrix and die mounted therein, or if so desired after the carrier has been withdrawn from the bolster-plate another matrix and die may be inserted in the carrier and die-holder.

In mounting the carrier in this manner it 35 will be apparent to those skilled in the art that a great saving of time is obtained in changing these parts over the prior art.

It has been found in actual practice that after the headed article has been formed and 40 ejected from the matrix by means of the die it will very often stick to the end of the die and become mashed on the following forward stroke of the cross-head, and in order to obviate this difficulty I have devised means for 45 positively ejecting the finished article from the die. To this end I mount on the upper end of the wedge 9 an L-shaped bracket 41, to the lower end of which is attached a fulcrum piece 42 to which is pivoted as at 43 50 one end of a lever 44, upon the opposite or free end of which is mounted by means of a bolt 45 a roller 46 for engaging a cam 47 secured to the bed-plate 1.

A stem-rod 48 having a bifurcated lower 55 end 49 is attached at an intermediate point to the lever 44 as at 50, the upwardly extending rod of which extends through an opening in the outwardly extending leg of the L-shaped bracket 41 and has a spring 51 interposed between the leg of the bracket and the bifurcated end 49 by means of which the lever is normally projected downwardly.

An adjustable kicker-holder 52 is also mounted on the lever 43 at an intermediate 60 point to which is pivoted as at 53 a kicker-

rod 54, extending downwardly therefrom through a guide 55 which is supported by a threaded stub-shaft 56 and clamped thereto by means of a nut 57. This threaded stub-shaft 56 has its lower end secured to the top 70 of the bolster-plate 21, while the upper portion is retained by means of a pair of clamp-bars 58 engaging lugs 59 which extend outwardly from the upper portion of the cross-head. The clamp-bars 58 are retained in position by means of nuts 57 and 60 on the stub-shaft and are further held by means of a bolt 61.

The stock 62, in the form of a rod or bar is fed by means of rolls 63 through the tube 64 and shear-blade 65 between the movable and stationary gripping dies 66 and 67 until the forward end of the stock engages the gauge 68 so as to cause the proper length of material to project beyond said gripping dies, where it is cut off by the lateral movement of the movable die 66 and clamped between the same in the usual well known manner.

The operation of my machine is as follows:—Assuming that the mechanism is in the position illustrated in Figs. 1 and 3, the stock bar or rod 62 having been fed by means of the rolls 63 through the shear-blade 65 and between the movable and stationary clamping dies 66 and 67 until the forward end of the bar engages the gauge 68. The movable die 66 is then moved laterally toward the stationary die 67 by any suitable means whereby a length of the bar is severed 100 and clamped between the clamping dies in alignment with the heading-die.

The rotation of the main drive shaft 5, which is continuously driven reciprocates the cross-head by means of the crank arm 4 105 and pitman connection 6, advancing the cross-head 3 thereby releasing the kicker-lever 14 and allowing the rear side of the shoulder 34 of the die-holder 29 to engage the face of the wedge and thereby withdrawing the die 28 into the matrix. As the cross-head 3 continues to advance the kicker-rod 54 is raised by means of the roller 46 engaging the cam 47 and the end of the blank will be upset which is the end of the working 110 stroke, as will be readily understood by referring to Figure 2 of the drawings.

By the continued rotation of the main drive shaft 5 the cross-head 3 will reciprocate backward to the position indicated in Figures 1 and 3 in which position the lower end of the kicker-lever 14 will engage the stop piece 15 and eject the headed article from the matrix 27 at the same time the kicker-rod 54 will detach the headed article from the end of the heading-die 28 as indicated in Fig. 1 115 of the drawings.

Although I have described and illustrated my invention in considerable detail, I do not 120 wish to be limited to the exact and specific 125

details thereof, as shown and described, but may use such modifications in, substitution for, or equivalents thereof, as are embraced within the scope of my invention, or as pointed out in the claims.

Having thus described my invention, what I claim and desire to secure by Letters Patent is:

1. In a machine for forming bolts and the like, comprising a reciprocating cross-head having a grooved forward face, an adjustable wedge seated in the groove, a kicker-lever pivotally mounted in the wedge, a bolster-plate attached to the cross-head, a carrier removably mounted in the bolster-plate, a matrix secured in the carrier, a die having a die-holder attached thereto which is mounted in the carrier and adapted to engage the pivoted kicker-lever for swinging it in one direction, and independent means for swinging the kicker-lever in the opposite direction. 75
2. In a machine for forming bolts and the like, comprising a reciprocating cross-head having a grooved forward face, an adjustable wedge having a channeled lower portion seated in the groove, a kicker-lever pivotally mounted in the channeled portion of the wedge, a bolster-plate attached to the cross-head, a carrier removably mounted in the bolster-plate, a matrix secured in the carrier, a die-holder having a die attached thereto mounted in the carrier and contacting with the kicker-lever for projecting the die and holder in one direction, and independent means mounted in the carrier for retracting the die and holder in the opposite direction. 80
3. In a machine for forming bolts and the like, comprising a bed-plate, a reciprocating cross-head mounted on the bed-plate having a grooved forward face, an adjustable wedge having a channeled lower portion mounted within the groove, a kicker-lever having its upper end pivoted within the channeled portion of the wedge, a bolster-plate attached to the cross-head, a carrier removably mounted in an opening in the bolster-plate, a matrix secured in the carrier, a die-holder having a die attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 85
4. In a machine for forming bolts and the like, comprising a bed-plate, a reciprocating cross-head mounted on the bed-plate having a vertically grooved forward face, an adjustable wedge having a channeled lower portion mounted within the groove, a kicker-lever pivoted at its upper end within the channeled portion of the wedge, a bolster-plate attached to the cross-head, a carrier removably mounted in the bolster-plate, a matrix secured in the carrier, a die having a die-holder attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 90
5. In a machine for forming bolts and the like, comprising means for feeding a stock-bar to the machine, means for shearing the stock-bar to form a blank and then clamping it between gripping dies, a reciprocating cross-head having a grooved forward face, an adjustable wedge seated in the grooved forward face of the cross-head, a matrix and reciprocating die for upsetting the end of the blank carried by the cross-head, means for ejecting the headed blank from the matrix, and means pivotally connected to the adjustable wedge for ejecting the headed blank from the die. 95
6. In a machine for forming bolts and the like, comprising means for feeding a stock-bar to the machine, means for shearing the stock-bar to form a blank and clamping it between the gripping dies, a reciprocating cross-head having a grooved forward face, an adjustable wedge seated in the grooved forward face of the cross-head, a matrix and reciprocating die for upsetting the end of the blank carried by the cross-head, means for advancing the die in the matrix to eject the headed blank from the matrix, and a kicker-rod pivotally connected to the adjustable wedge carried by the cross-head adapted to contact with the headed blank on the return stroke of the cross-head and detach the headed blank from the die. 100
7. In a machine for forming bolts and the like, comprising means for feeding a stock-bar to the machine, means for shearing the stock-bar to form blanks and then clamping them between gripping dies, a reciprocating cross-head having a grooved forward face, an adjustable wedge seated in the grooved forward face of the cross-head, a bolster-plate attached to the cross-head, a carrier removably mounted in the bolster-plate, a matrix secured to the carrier, a die-holder having a die attached thereto mounted in the carrier and adapted to reciprocate therein to upset the end of the blank in the matrix on the forward stroke of the cross-head, means for advancing the die and holder to eject the headed blank from the die. 105
8. In a machine for forming bolts and the like, comprising a bed-plate, a reciprocating cross-head mounted on the bed-plate having a grooved forward face, an adjustable wedge having a channeled lower portion seated in the groove, a kicker-lever having its upper end pivoted within the channeled portion of the wedge, a bolster-plate attached to the cross-head, a carrier removably mounted in the bolster-plate, a matrix secured in the carrier, a die having a die-holder attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 110
9. In a machine for forming bolts and the like, comprising a bed-plate, a reciprocating cross-head mounted on the bed-plate having a vertically grooved forward face, an adjustable wedge having a channeled lower portion seated in the groove, a kicker-lever pivoted at its upper end within the channeled portion of the wedge, a bolster-plate attached to the cross-head, a carrier removably mounted in the bolster-plate, a matrix secured in the carrier, a die having a die-holder attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 115
10. In a machine for forming bolts and the like, comprising means for feeding a stock-bar to the machine, means for shearing the stock-bar to form blanks and then clamping them between gripping dies, a reciprocating cross-head having a grooved forward face, an adjustable wedge seated in the grooved forward face of the cross-head, a bolster-plate attached to the cross-head, a carrier removably mounted in the bolster-plate, a matrix secured to the carrier, a die-holder having a die attached thereto mounted in the carrier and adapted to reciprocate therein to upset the end of the blank in the matrix on the forward stroke of the cross-head, means for advancing the die and holder to eject the headed blank from the die. 120
11. In a machine for forming bolts and the like, comprising a bed-plate, a reciprocating cross-head mounted on the bed-plate having a grooved forward face, an adjustable wedge having a channeled lower portion seated in the groove, a kicker-lever having its upper end pivoted within the channeled portion of the wedge, a bolster-plate attached to the cross-head, a carrier removably mounted in the bolster-plate, a matrix secured in the carrier, a die having a die-holder attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 125
12. In a machine for forming bolts and the like, comprising a bed-plate, a reciprocating cross-head mounted on the bed-plate having a vertically grooved forward face, an adjustable wedge having a channeled lower portion seated in the groove, a kicker-lever pivoted at its upper end within the channeled portion of the wedge, a bolster-plate attached to the cross-head, a carrier removably mounted in the bolster-plate, a matrix secured in the carrier, a die having a die-holder attached thereto mounted in the carrier and contacting with the kicker-lever, a shoulder formed on the die-holder, an abutment formed on the carrier, a spring interposed between the shoulder and the abutment and adapted to retract the die and holder, and a stop mounted on the bed-plate for engaging the lower end of the kicker-lever and adapted to advance the die and holder within the carrier. 130

headed blank, and a kicker-rod pivotally connected to the adjustable wedge carried by the cross-head adapted to contact with the headed blank after it has been ejected from the matrix to positively detach the headed blank from the die.

8. In a machine for forming bolts and the like, comprising means for feeding a blank to the machine, a reciprocating cross-head having a grooved forward face, an adjustable wedge seated in the groove, a kicker-lever pivotally mounted in the wedge, a bolster-plate attached to the cross-head, a carrier removably mounted in the bolster-plate, a die having a holder attached thereto mounted in the carrier adapted to upset the end of the blank in the matrix on the forward stroke of the cross-head, said die-holder contacting with a kicker-lever for advancing the die and holder after the upsetting operation to eject the headed blank from the matrix, a spring actuated lever pivoted to the wedge, a kicker-rod mounted on the spring pressed lever adapted to contact with the headed blank after it has been ejected from the matrix and positively detach it from the die.

9. In a machine for forming bolts and the like, comprising means for feeding a stock-bar to the machine, means for shearing the stock-bar to form blanks by means of the gripping dies, a reciprocating cross-head having a grooved forward face, an adjustable wedge seated in the groove, a bolster-plate attached to the cross-head, a carrier removably mounted in the bolster-plate, a matrix secured to the carrier, a die having a holder attached thereto mounted in the carrier and adapted to reciprocate therein to upset the end of the blank in the matrix on the forward stroke of the cross-head, means for advancing the die and holder to eject the headed blank, a bracket attached to the wedge, a lever having one end pivoted to the bracket, a roller mounted on the opposite end of the lever adapted to engage a cam attached to the bed-plate of the machine, a stem-rod pivoted to the lever and extending through a leg of the bracket, a spring mounted thereon interposed between the bracket and lever, and a kicker-rod having a pivoted connection on the lever adapted to contact with the headed blank after it has been ejected from the matrix to positively detach the headed blank from the die.

10. In a machine for forming bolts and the like, comprising means for feeding a stock-bar to the machine, means for shearing the stock-bar to form blanks, and then clamping them between gripping dies, a reciprocating cross-head, an adjustable wedge mounted on the cross-head, a matrix and reciprocating die carried by the cross-head, means for upsetting the blank in the matrix and ejecting it by means of the die, a bracket attached to the

wedge, a lever pivoted at one end to the bracket, a roller mounted on the opposite end of the lever for engaging a cam mounted on the bed-plate of the machine, a spring adapted to hold the roller on the cam, a kicker-rod having a pivoted connection on the lever and extending through a guide adapted to contact with the headed blank after it has been ejected from the matrix to positively detach the headed blank from the die.

11. In a machine for forming bolts and the like, comprising means for feeding a stock-bar to the machine, means for shearing the said stock-bar to form blanks, means for gripping one end of the blank between clamping dies and allowing the opposite end to project beyond the clamping dies, a reciprocating cross-head having a grooved forward face, an adjustable wedge seated in the grooved forward face of the cross-head, a matrix carried by the reciprocating cross-head, a die mounted in the matrix adapted to reciprocate independently of the cross-head for upsetting the projecting end of the blank on the forward stroke of the cross-head and eject the headed blank from the matrix on the backward stroke of the cross-head, a kicker-rod pivotally connected to the adjustable wedge and operated by the reciprocation of the cross-head and adapted to engage and positively detach the headed blank from the die.

12. In a machine for forming bolts and the like, comprising a bed-plate, a reciprocating cross-head mounted thereon, a matrix having a reciprocating die mounted therein carried by the cross-head and adapted to upset the end of the blank to form a head thereon within the matrix on the forward stroke of the cross-head and then eject the blank from the matrix on the forward stroke of the cross-head, an L-shaped bracket movable with the cross-head, a lever pivoted at one end to the bracket, a roller mounted on the opposite end of the lever for engaging a cam by means of which the lever is raised on the forward stroke of the cross-head, a stem-rod pivoted to the lever and extending through one leg of the bracket, a spring on the stem-rod interposed between the lever and the bracket for holding the roller at all times in contact with the cam, a kicker-rod pivotally connected to the lever and extending through a guide attached to the cross-head and adapted to engage and positively detach the headed blank from the die on the backward stroke of the cross-head.

13. In a machine for forming bolts and the like, comprising a reciprocating cross-head having a grooved forward face, an adjustable wedge seated in the groove, a bolster-plate attached to the cross-head, a carrier removably mounted in the bolster-plate, a matrix secured to the carrier, a die-holder having a die attached thereto mounted in the carrier,

resilient means mounted in the carrier for retracting the die-holder on the forward stroke of the cross-head, a kicker-lever pivotally mounted in the wedge for engaging and advancing the die-holder on the backward stroke of the cross-head, a kicker-rod carried by the wedge to engage and positively detach the headed blank from the die, a cam for actuating the kicker-rod in one direction and 10 resilient means for actuating the kicker-rod in the opposite direction to that of the cam.

14. In a machine for forming bolts and the like, the combination with feeding, shearing and gripping mechanism for the blank, a reciprocating cross-head having a vertically grooved forward face, an adjustable wedge seated in the grooved forward face of the cross-head, means carried by the cross-head for forming a head on the blank, a kicker-rod 20 carried by the adjustable wedge seated in the cross-head for ejecting the headed blank from the die, a cam for actuating the kicker-rod in one direction mounted on the frame, and resilient means movable with the cross-head 25 for actuating the kicker-rod in the opposite direction to that of the cam.

15. In a machine for forming bolts and the like, comprising a reciprocating cross-head, a bolster-plate attached to the cross-head, a carrier 30 removably mounted in the bolster-plate, a matrix secured to the carrier, a die-holder having a die attached thereto mounted in the carrier, an adjustable wedge mounted in the cross-head for engaging the rear end of the carrier, resilient means mounted in the carrier for sliding the die-holder in one direction, and a kicker-lever pivoted to the wedge 35 for engaging the rear end of the die-holder for sliding the die-holder in the opposite 40 direction.

16. In a machine for forming bolts and the like, comprising a cross-head having a grooved outer face, an adjustable wedge seated in the grooved outer face of the cross-head, means for reciprocating the cross-head, a bolster-plate attached to the cross-head, a carrier 45 removably mounted in the bolster-plate having its rear end engaging the wedge and adapted to be adjusted thereby, a matrix secured to the carrier, a die-holder having a die attached thereto mounted in the carrier, means mounted in the adjustable wedge for engaging and advancing the die-holder in the carrier and resilient means 50 mounted in the carrier for retracting the die-holder.

17. In a machine for forming bolts and the like, comprising a reciprocating cross-head, a bolster-plate attached to the cross-head, a carrier mounted in the bolster-plate, a matrix secured to the carrier, adjustable means mounted in the cross-head for engaging the rear end of the carrier, a die 55 adapted to reciprocate within the matrix, resilient means mounted in the carrier for

retracting the die in the matrix on the forward stroke of the cross-head, and independent means carried by the adjustable means mounted in the cross-head for engaging the die-holder and advancing the die in the matrix on the backward stroke of the cross-head. 70

18. In a machine for forming bolts and the like, comprising a bed-plate having a stop mounted thereon, a reciprocating cross-head, an adjustable wedge mounted in the cross-head, a bolster-plate attached to the cross-head, a carrier mounted in the bolster-plate, a matrix secured to the carrier, a die adapted to reciprocate within the matrix, a die-holder having a shoulder formed thereon mounted in the carrier, an abutment formed in the carrier, a spring interposed between the shoulder and the abutment for retracting the die in the matrix on the forward stroke of the cross-head, and a swinging pivoted kicker-lever carried by the adjustable wedge in the cross-head adapted to engage the die-holder and contact with the stop for advancing the die in the matrix on the backward stroke of the cross-head. 80

19. In a machine for forming bolts and the like, comprising a reciprocating cross-head having a vertically grooved forward face, an adjustable wedge seated in the grooved face of the cross-head, an opening formed in the bolster-plate, a carrier having its rear end engaging the wedge and removably mounted in the bolster-plate, a matrix mounted in the carrier, a die having a die-holder attached thereto adapted to reciprocate in the matrix within the carrier, independent means pivoted to the wedge and mounted in the carrier for projecting and retracting the die and holder, a split formed 95 in the bolster-plate between the opening and the side thereof, ears formed at the sides of the split, and a clamping bolt extending through the ears adapted to clamp the carrier between the sides of the opening in the 100 bolster-plate. 105

20. In a machine for forming bolts and the like, comprising a reciprocating cross-head having a vertically grooved forward face, an adjustable wedge seated in the grooved face of the cross-head, a bolster-plate attached to the cross-head, an opening formed in the bolster-plate, an integral boss formed on the bolster-plate surrounding the opening, a carrier having its rear end engaging the wedge and removably mounted in the bolster-plate, a die having a die-holder attached thereto adapted to reciprocate in the matrix within the carrier, independent means pivoted to the wedge and mounted in the carrier for projecting and retracting the die and holder within the carrier, a split formed in the bolster-plate and boss between the opening and the side thereof, ears formed 115 at the sides of the split, a clamping bolt 120

125

130

extending through the ears adapted to clamp the carrier between the sides of the opening in the bolster-plate, and a set-bolt extending through the boss for engaging the carrier.

5 In testimony whereof I hereunto affix my signature.

WILLIS H. CASTNER.
